UNITED STATES PATENT OFFICE.

MAX PALEY, OF MONTICELLO, NEW YORK.

METHOD OF VARYING THE SIZE OF GARMENTS.

Application filed December 24, 1926. Serial No. 156,892.

This invention consists in varying the proportionate size of a finished garment or coat, such as those worn by men and boys, in a manner so as to make a garment larger or 5 smaller, as required, to fit the person for whom it is intended, to be of further use to such person.

The drawing forming a part of the following specification illustrates certain steps 10 followed in carrying out the method of the present invention, and in which—

Figure 1 is an inside view of a coat, substantially one-half of the coat being shown, and the side seam being completely opened 15 and the armhole seam being partly open preparatory to the relative movement of the front of the coat with respect to the back of the coat, and the resewing of the seams.

Fig. 2 is a view similar to that shown in 20 Fig. 1, but showing the front of the coat moved down with respect to the back of the coat and resewed preparatory to the rehemming of the skirt of the front to refinish the coat to make it larger in proportionate size, 25 particularly around the breast and shoulders.

Fig. 3 is a view similar to that shown in Fig. 2 except that the coat is made smaller 30 by moving the front up with respect to the back.

Referring now more particularly to the several views of the drawing, it will be apparent that there is illustrated in Fig. 1 substantially one-half of a coat, which when 35 completed includes two front sections 10 and a back section 11 which are secured together and form a side seam 12 which extends from the skirt portions of the front and back upwardly to the armhole 13, at which is 40 formed what is known as an armhole seam 14; the armhole seam 14 being formed as a result of the sleeve of the coat being attached to the front and back sections 10 and 11. At the armhole seam there is usually in- 45 corporated a tape 15 which maintains the shape at this point and prevents the parts from ripping away from each other.

It has been found that a garment of this kind may be altered to either make the same 50 larger or smaller by completely opening each of the side seams 12 and by partly opening

each of the armhole seams 14. It is also necessary to cut each of the armhole tapes 15. Then to enlarge the garment so that there will be more room at the breast and 55 shoulders, the front sections 10 are moved or pulled downwardly with respect to the back section 11 which brings a skirt portion of each of the front sections 10 below the lower edge or hem of the back section, as indicated at 16 in Fig. 2. All of the opened seams are then resewed, and the skirt portions 16 of the front sections 10 are taken up 60 and rehemmed to completely refinish the coat. This will result in the coat being 65 larger about the breast and particularly around the shoulders. Incidental to the steps of this method above mentioned, the tape 15 will be resewed, and if necessary a small piece may be inserted, and the lining 70 will be resewed.

When it is desired to make a finished garment smaller it is only necessary to go through the steps hereinbefore mentioned, except that the front sections 10 will be 75 moved upwardly with respect to the back section 11. This will result in a skirt portion of the back section 11 being brought below the lower edges of the front sections 10, as indicated at 17. The said portion 17 80 will be taken up and restitched, even with the lower edges of the front section 10.

I claim:

1. The herein described method of varying the proportionate size of a finished coat which consists in completely opening the side seams and partly opening the armhole seams, moving the back of the coat relatively to the front of the coat along the lines of the former side seams, restitching all of the 85 opened seams, and then taking up and rehemming the projecting skirt portion of the coat.

2. The herein described method of enlarging a finished coat which consists in completely opening the side seams and partly opening the armhole seams, moving the front of the coat up with respect to the back of the coat, restitching all of the opened seams, and taking up the hem on the skirt of the 95 back of the coat.

3. The herein described method of varying

the proportionate size of a finished coat having tapered armholes which consists in completely opening the side seams and partly opening the armhole seams, severing the 5 armhole tapes, moving the back of the coat relatively to the front of the coat along the lines of the former side seams, inserting a

piece in each of the armhole tapes, letting out portions of the lining of the coat, re-stitching all of the opened seams, taking up ¹⁰ the projecting skirt portion, and sewing together the portions of the lining let out.

MAX PALEY.
